UNITED STATES PATENT OFFICE.

EDWIN L. HALL, OF DEAVERTOWN, OHIO.

HAY ELEVATOR AND CARRIER.

SPECIFICATION forming part of Letters Patent No. 274,817, dated March 20, 1883.

Application filed February 17, 1883. (No model.)

To all whom it may concern:

Be it known that I, EDWIN L. HALL, of Deavertown, in the county of Morgan and State of Ohio, have invented a new and useful Improvement in Hay Elevators and Carriers; and I do hereby declare that the following is a full, clear, and exact description of the same.

My invention relates to hay elevators and carriers of that class in which the hoisting-rope is suspended from a carriage or truck which runs or slides on a track to convey the load, after it is hoisted, to its place of deposit.

In elevators and conveyers of this class, when used in barns, the track, consisting of wooden beam or iron bar or rod, is ordinarily extended across the floor or wagon-way and over the bay or scaffold on each side, so that the hay, when unloaded from the wagon, may be conveyed either to one side or the other. With the track so arranged it has been necessary, as the trucks have heretofore been constructed, whenever the scaffold or bay on one side had been filled, or for any other reason it was desirable to shift the discharge from one side to the other, to reverse the truck upon the way or track and to shift the ropes to corresponding position on the other side. This has always been a matter of great inconvenience, since it required climbing to the central part of the track over the floor in order to reverse the truck.

The object of my invention is to obviate this necessity of climbing to reverse the truck in order to allow it to run in an opposite direction.

To this end my invention consists essentially of a reversible or swiveled support for connecting the rope-pulley and rope to the truck, whereby the said support may be reversed by the swaying of the rope and without the necessity of climbing to the truck or track.

My invention further consists of the special details of construction whereby my invention is the better carried into effect.

In the accompanying drawings, Figure 1 is a side elevation of my improved apparatus. Fig. 2 is a central longitudinal section of the truck, with the way in side elevation. Fig. 3 is a bottom view of the truck. Fig. 4 is a section on line xx of Fig. 2. Fig. 5 is a transverse section on line yy of Fig. 1. Fig. 6 is a bot-

tom view of the truck with the turn-table removed.

In these drawings, A represents the track or way, which may be of any suitable material and suspended by any suitable means. As shown, it is a beam suspended by rods and rectangular in cross-section. The truck B runs upon this, having overlapping flanges b , which bear upon the upper side of the beam, 60 with or without rollers to lessen friction. The space a between the flanges permits the truck to pass the suspending-rods. In the bottom of the truck is a chamber, c , in which are pivoted two levers, d . The outer ends of these are 65 bent upward, so that when the inner ends lie upon the bottom of the chamber the outer ends are raised to engage with blocks ee on the under surface of the track. The inner ends of the levers are cut away and lap, as shown at f , Fig. 4, 70 these inner and lapping ends falling just over the hole g in the bottom of the truck, where the stem of the hoist-block enters from below. It will be observed that the outer ends of the levers engage with the blocks ee on their inner 75 faces, and thus lock the truck against movement in either direction. This locking takes place automatically in the apparatus, when the truck reaches its proper position over the load, by the action of the inner weighted ends of 80 said levers. These inner ends of the levers are raised by the stem h of the hoist-block, as explained, when the said block has been raised its full height and locked to the truck. The locking of this stem of the hoist-block is effected by means of pivoted jaws kk in a recess in the bottom of the truck, under the center of the truck, and under the ends of the two levers. The jaws are fitted to receive and hold the head l of the block-stem. They are pressed 85 together by means of a spring, m , and opened by a lever, n , pivoted between the ends o of the jaws, so that motion of the lever n either way will separate the jaws and release the block. This motion of the lever n is effected 90 by means of a bracket, D , on the track, which projects downward into the path of the end of the lever n , so that the said lever may be turned aside as the truck moves past the bracket, but which still permits the lever n to slip by. 95 Whichever way, therefore, the truck moves, it will cause the lever n to strike the bracket

and release the block, and in that position it remains until the load is raised to bring again the block-stem to the jaws. Of course the stops on the way or track are set in proper relation to the bracket, so that the bracket will move the lever *n* and release the block when the truck is in proper position to allow the block and fork to descend to the load or operator.

- 10 Underneath the truck is the turning-plate *E*, to which the rope *p* is attached, and which also carries the pulley *q*. This plate is held to the under side of the truck by overlapping cleats *r r*. A hole, *s*, registers with the jaws, and is preferably flaring to receive and guide the conical or tapering end of the stem. The rope *p* is attached to one side and the pulley *q* to the opposite, the rope passing through the moving block *t*, and thence to the pulley *g*, and thence to an ordinary pulley attached by ordinary clamp to a rafter or other support. It will be apparent, therefore, that in order to reverse the truck and shift it from one side to the other it is only necessary to detach the rafter-clutch (which is ordinarily done with a pole, requiring no climbing) and to shift and reattach it by the same means to a rafter on the other side. Then the strain of the rope will keep the turning-disk, with the pulley *q*, turned in the proper direction to which it may have been turned by swaying the rope from below.

The described form of turning-plate is a convenient one for the kind of clutch mechanism provided to retain the head of the block-stem; but it will be obvious that this turning or swiveling connection between the pulley and rope attachments and the truck may be greatly varied in shape and details. For example, it may be in the form of a swivel and the clutch devices modified to fit this construction. I do not limit myself in this respect, provided a suitable swiveled or turning device be attached to the truck, in connection with suitable stops and clutch for the support of the block.

I provide, also, in connection with the hereinbefore-described devices, means for returning the truck from one or either direction. This consists of a pair of horizontal sheaves, 1 50 1, in a cross-bar, *u*, on the bracket, through which runs a rope, 2, connected to the truck and passing through a pulley placed at any de-

sired point. A weight (not shown) on the free end brings back the truck alike from either direction.

It will be understood that any suitable hay-fork may be attached to the lower end of the moving block.

The device may of course be used for hoisting and conveying any kind of merchandise.

Having thus described my invention, what I claim is—

1. A hay elevator and carrier consisting of a truck and suitable way, stops to arrest the truck properly over the load, a hoisting-rope and pulleys, suitable catch to take hold of and retain the loaded fork when elevated, suitable releasing devices, and a reversible connection between the pulley and rope attachment and the frame of the truck, whereby the rope is connected to the truck reversibly, substantially as described.

2. The way *B*, extending over the floor to either side, a moving truck, an automatic catch adapted to hold the truck in place and to be released by the movable block, a clutch for automatically catching and holding the block, and means for releasing the same, a turning device attached to the under side of said truck, and provided with a rope and pulley attached thereto, whereby the movement of the truck may be made in either direction, substantially as described.

3. The combination of the truck *B*, pivoted levers lapping over clutch and weighted on inner ends, the pivoted jaws, the spring and opening-lever *n*, and the turning-plate and pulley and rope with movable pulley having headed stem, substantially as described.

4. The combination of the truck having devices whereby it may be moved either way without turning said truck, and bracket on the way, provided with sheaves, and a cord passing between said sheaves and attached to the truck, a pulley, and a weight, all substantially as described.

In testimony whereof I have signed my name to this specification in the presence of two subscribing witnesses.

EDWIN L. HALL.
